FOLDING MACHINE

Charles Hess, Yonkers, N. Y., assignor to S & S
Corrugated Paper Machinery Co., Inc., Brooklyn, N. Y., a corporation of New York

Application November 20, 1947, Serial No. 787,158

2 Claims. (Cl. 93—52)

1

My present invention relates to folding machines particularly adapted to fold large size corrugated board or solid fibre box blanks about their fold lines so that the edges of the folded panels meet edge to edge in order that they may be taped or stitched to form a folded box tube which may later be erected to form a container.

Heretofore, in the construction and operation of folding machines for heavy box blanks, reliance has been placed on the utilization of specific mechanisms at different positions in the machine to start the fold, pleat the fold and press the folded panels down. This has required a multiplicity of mechanical operations, including moving tapes, moving platforms, folding plates, pressure rolls, deflecting plates and associated operating mechanisms, including racks and pinions, eccentric gears, changing sprockets and various other elements, all of which required individual adjustment in order to change from one size of box blank to the other and also required skilled and detailed operation, attention, replacement and repair.

My invention contemplates the utilization of a pair of deflecting bars cooperating with folding slats to deflect the side panels upwardly as the box blank is moved steadily through the machine.

The pair of folding bars thus start at or below the level of the bed of the machine over which the box blank moves and are positioned outside of the folding slats. The folding bars then rise toward the forward end of the machine, at the same time being inclined toward each other and thus toward the central axis of the bed of the machine.

These bars thus cooperating with the folding slats raise the panels of the blank to a vertical position. An additional set of folding bars oppositely directed, extending down toward the forward end of the machine and extending inwardly toward the central axis of the machine then bend the panels from the vertical position as the box blank moves over down to a position where they meet and are in surface to surface engagement with the remainder of the blank.

By this means, therefore, the only moving operating mechanism needed is the mechanism for moving the blank through the machine. All of the other elements are stationary and operate by reason of the movement of the blank with respect thereto.

The folded blank may then be fed further forward, either into a taping machine, a stitching machine or any other machine which will interengage the seam at the edges of the folded blank.

5 The primary object of my invention, therefore, is the provision of novel folding mechanism for heavy box blanks made of corrugated board, solid fibre board or other appropriate material.

10 Another object of my invention is the provision of novel folding mechanism for box blanks wherein all of the folding elements operate by reason of the movement of the blank with respect thereto and without any independent movement of their own.

15 Another object of my invention is the provision of novel folding elements for a folding machine comprising a pair of bars rising upwardly toward the forward end of the machine and inwardly directed toward the central axis of the machine, the pair of bars starting at or below the level of the bed of the machine across which the paper blank moves.

20 Another object of my invention in connection with the foregoing upwardly directed folding bars is the provision of an additional set of downwardly directed folding bars starting at about the point where the first set of folding bars completes the upward fold of the panel and

25 operating to press down the panels through the remainder of the distance necessary to complete the fold.

20 The foregoing and many other objects of my invention will become apparent in the following 30 description and drawings in which:

Figure 1 is a side view of my novel folding machine.

Figure 2 is a top view of my novel folding machine.

35 Figure 3 is a schematic view in perspective of the operating elements of my novel folding machine.

40 Referring now to the figures, the main bed or platform 10 of my novel folding machine is mounted in any suitable manner on standards 11, 12. Brackets 13 are provided at the feed end of the machine to support the shaft 14 which carries the sprockets 15. Brackets 17 are provided at the delivery or forward end of the machine to support the shaft 18 which carries the sprockets 19.

45 A pair of sprockets 15 and a similar pair of sprockets 19 are used at opposite ends of the machine, as shown, in order to support between them a pair of continuous chains 20 and 21. The chains 20 and 21 may be driven in any suitable manner as, for instance, by the electric motor 25 mounted on the bracket 26 supported on standard 12 and connected by pulley 27, belt 28 and pulley

29 to drive the shaft 18, thereby in turn driving the sprockets 19 and the chains 20 and 21.

Preferably, the control starting and stopping of motor 25 should be mounted at the feed or delivery end of the machine and the motor may also be mounted on standard 11 instead of on standard 12.

The chains 20 and 21 carry across them a plurality of spaced blank feeding slats 30 adapted to engage the bottom blank of a stack and move it out while leaving the remaining blanks in the stack. Adjustable side gauges 33 and 34 and adjustable front gauges 35 and 36 define the stack of blanks 37. Side gauges 33 and 34 are supported at their lower edges on the main bed 10 of the machine but are held in vertical position by the brackets 38, 39 which are secured thereto in any suitable manner, the said brackets each having an opening which receives the rectangular shaft 40 supported in standards 41 and 42 secured to the outer sides of the bed of the machine.

The brackets 38 and 39 may be slid along the bar 40 and the adjustment thus obtained may be secured by the set screws 44, 45 carried by brackets 38 and 39 and rotatable to bear frictionally against the bar 40.

The front gauges 35 and 36 are so arranged that they just clear the top surface of the bed 10 of the machine by a gap 47 slightly more than the thickness of a single blank. Front gauges 35 and 36 are also supported on brackets 50 and 51 carried by the cross bar 40 and adjustably positionable by being slideable along the bar, the adjustment being retained by the set screws 52, 53. The front gauges 35 and 36 also carry secured thereto in any suitable manner the folding slats 55 and 56.

The flanges 57 and 58 thereof, respectively, are secured to the gauges 35 and 36. The outer edges 56a and 55a of the folding slats are adjusted so that they are aligned with the fold or score lines 60, 61 of the blanks 37 which are to be folded.

The bed 10 of the machine is provided with the longitudinal cut-outs 70 and 71 to permit the means for attaching the slats 30 to the chains to project upwardly to engage the slats 30 which move on the upper surface of the bed 10.

Openings 72 and 73 are provided at the end of the travel of chains 20 and 21 to permit the slats to move down from the bed of the machine and up to the bed of the machine once more. The folding bars 80 and 81 are secured, respectively, at their feed ends at 83 and 82 preferably in openings in the bed 10 of the machine so that the feed ends of the folding bars 80 and 81 start below the level of the folding slats 55 and 56 and so that any blank which passes thereover will necessarily ride up on to the folding bars 80 and 81.

As shown in Figures 1 and 3, the folding bars 80 and 81 rise slowly toward the forward end of the machine and as shown in Figures 2 and 3 the folding bars 80 and 81 are inwardly directed toward the central longitudinal axis of the bed 10 of the machine toward the delivery or forward end of the machine. The folding bars 80 and 81 meet at their forward or delivery end at 84 where they are interconnected for purposes of rigidity, the meeting ends 84 being upwardly bent at 85 so as to ensure that the meeting ends will clear the highest flap which may be folded by the machine.

The bars 80 and 81 act to move the side flaps 37a and 37b defined by fold lines 60 and 61 of

the blank 37 from the flat or horizontal position shown at the bottom of the stack in Figures 1 and 2 through the position marked A in Figure 3 where the panels 37a and 37b are first deflected up to the position marked B in Figure 3 where the panels 37a and 37b are substantially vertical.

The panels 37a and 37b then move between the outwardly projecting ends 100, 101 of the fold down bars 102, 103. The ends 100 and 101 of the fold down bars 102, 103 project outwardly to a position beyond the bars 80 and 81 at the points 104 and 105 where they connect.

The bars 102 and 103 are inwardly directed toward the forward or delivery end of the machine while, at the same time, they are downwardly directed and terminate in the hold down slot 106.

As the blank moves from position B of Figure 3 through to the folded position C, the vertical panels 37a and 37b at position B move between the ends 100 and 101 of the fold down bars 102 and 103 and are then folded down about the edges 55a and 56a of the folding slats 55 and 56 until they are rotated into surface to surface engagement with the main body of the blank when the blank is now folded as shown at C of Figure 3.

The bars 102 and 80 may be interconnected at 104, with, of course, the bar 102 outside of the bar 80. Similarly, the bars 103 and 81 may be interconnected at 105 with again the bar 103 outside the bar 81.

Further and in order additionally to rigidify the folding structure, supporting brackets 110 and 111 may be connected to the interconnected points 104 and 105 of the folding bars, the said supporting brackets 110 and 111 being anchored, respectively, at 112, 113 at the outer sides of the bed of the machine.

The hold down slat 106 may be adjustably positioned in accordance with the thickness of the blank to be folded and the degree of pressure desired on the finished folded blank by the set screw 120 passing through the threaded opening in the cross bar 121 supported by brackets 122, 123 across the machine. The screw 120 as seen in Figure 1 bears on the upper surface of slat 106 so that the adjustment thereof determines the maximum clearance between the bed of the machine and slat 106.

In operation, the slats 30 successively engage and feed out the bottom blank 37 in the stack of blanks, the remainder of the blanks being held back by the gauges 35 and 36, the blank to be fed out passing through the gap 47. The fold lines 60 and 61 of the blank which is fed out are just outside the edges 55a and 56a of the folding slats 55 and 56. The panels 37a and 37b move up on the folding bars 80 and are deflected upwardly thereby by the cooperation of the folding bars 80 and 81 with the folding slats 55 and 56 in conjunction with the forward movement of the box blank.

When the box blank panels have been folded to vertical position, then the folding bars 103 and 104 receive the vertical panels in order to complete the fold rotating them down into surface to surface engagement with the box blank. The hold down slat 106 then retains the blank in the folded position until it is fed out of the folding machine to a taper, stitcher, or other suitable machine for interconnecting the meeting edges of the folded panels.

When desired, additional bracing elements as,

for instance, the braces 130, 130 may be used for rigidifying the folding bars 80 and 81. No adjustment of the folding bars 80 and 81 or of the folding bars 103 and 104 is required since it is only necessary that these bars are engaged by a portion of panels 37a and 37b of the blank, and it is not material whether these bars engage initially the outer portion of panels 37a and 37b remote from the fold lines or a portion of panels 37a and 37b closer to the fold lines as long as the portion of the blank on each side outside the fold lines 60 and 61 are first engaged or pass over and on to the folding bars 80 and 81.

The only adjustment needed is the adjustment of front gauges 35 and 36 and the folding slats 55 and 56 which move therewith in order to cause the edges 55a and 56a of the folding slats 55 and 56 to coincide with the fold lines 60 and 61 of the blank to be folded.

The outer limit of blank size which may be folded by the machine is one in which the folding edges 56a and 55a of the folding slats 56 and 55 are moved close to the folding bars 80 and 81 without, however, touching the same. The smallest blank which may be folded is one in which when the folding slats 56 and 55 are brought together, the width of the panels 37a and 37b is less than the initial distance between either of the folding edges 56a or 55a and the associated folding bar 80 or 81 at the point where the associated folding bar 80 or 81 is at the level of the folding edge.

Consequently, a great range of blank sizes may be folded without requiring any adjustment of the folding mechanism, the only adjustment required being the movement of the folding slats 55 and 56 carried by the front gauges 35 and 36 to a position where the edges of the folding slats coincide with the fold lines 60 and 61.

By the means herein shown, therefore, I have shown a simplified box blank folding mechanism utilizing no moving parts other than the movement of the blank through the machine in order to produce the folding operation and having no elements which may become out of order by reason of constant use. The machine is readily adjustable by a single adjustment to fold blanks of different sizes having different spacings between their fold lines 60 and 61 and requires no other attention.

In the foregoing, I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. A folding machine for folding flat box blanks having predetermined fold lines into tubular form, the said box blanks each having a pair of outer panels defined by fold lines, which panels when folded over toward each other against the blank body will meet at their edges to form a seam; said machine comprising a horizontal platform, means for moving a box blank longitudinally along said horizontal platform; a pair of flat folding bars extending longitudinally along said horizontal platform; the outer edges of said folding bars being each positionable along the path of travel of a fold line in the box blank defining an outer panel; the box blank moving beneath said folding bars and the panels to be folded projecting beyond said folding bars; folding apparatus including a stationary inclined bar lo-

cated on each side of said platform and extending longitudinally of the platform; each inclined bar extending beneath the path of travel of the box blank panel and outside of the folding bar on its side at the end of the inclined bar over which the box blank first moves; each inclined bar extending at an acute angle to the platform to a point elevated above the platform in the direction of movement of the box blank; said inclined bars being integrally joined to each other at said elevated point, said inclined bars and said folding bars cooperating with the means for moving the box blank to fold the outer panels upwardly as the box blank moves along the platform, said folding apparatus also including additional stationary inclined bars extending longitudinally of said platform extending at an opposite angle to said platform from the first-mentioned inclined bars and positioned to engage the outer surfaces of the upwardly folded panels and press them down toward each other and the main body of the blank as the blank moves along the platform; said additional stationary bars converging toward the longitudinal axis of the platform as they descend and terminating in an elongated pressure plate disposed to maintain the pressed down panels in flat position, including a pressure screw disposed to bear on said pressure plate and to be manually adjusted to vary the pressure thereon.

2. A folding machine for folding flat box blanks having predetermined fold lines into tubular form, the said box blanks each having a pair of outer panels defined by fold lines, which panels when folded over toward each other against the blank body will meet at their edges to form a seam; said machine comprising a horizontal platform, means for moving a box blank longitudinally along said horizontal platform; a pair of flat folding bars extending longitudinally along said horizontal platform; the outer edges of said folding bars being each positionable along the path of travel of a fold line in the box blank defining an outer panel; the box blank moving beneath said folding bars and the panels to be folded projecting beyond said folding bars; folding apparatus including a stationary inclined bar located on each side of said platform and extending longitudinally of the platform; each inclined bar extending beneath the path of travel of the box blank panel and outside of the folding bar on its side at the end of the inclined bar over which the box blank first moves; each inclined bar extending at an acute angle to the platform to a point elevated above the platform in the direction of movement of the box blank; said inclined bars being integrally joined to each other at said elevated point, said inclined bars converging toward the longitudinal axis of the platform as they rise therefrom; said inclined bars and said folding bars cooperating with the means for moving the box blank to fold the outer panels upwardly as the box blank moves along the platform; said folding apparatus also including additional stationary inclined bars extending longitudinally of said platform extending at an opposite angle to said platform from the first-mentioned inclined bars and positioned to engage the outer surfaces of the upwardly folded panels and press them down toward each other and the main body of the blank as the blank moves along the platform; said additional stationary bars converging toward the longitudinal axis of the platform as they descend and terminating in an elongated pressure plate disposed to maintain the

pressed down panels in flat position, including a pressure screw disposed to bear on said pressure plate and to be manually adjusted to vary the pressure thereon.
